UNITED STATES PATENT OFFICE

ROBERT W. GIBB, OF EAST DEDHAM, MASSACHUSETTS

ANCHOR

Application filed March 21, 1931. Serial No. 524,273.

My invention relates to anchors, but more particularly has reference to anchors of the mushroom type, and has for its object to provide an anchor of this description that will fold compactly so that it may be easily stowed, will have ample weight when in use, will grip quickly and hold securely.

Referring to the accompanying drawings which are to be read in connection with the following description,

Figure 1 is a view of the anchor as it appears when in use with an ordinary knot in the anchor rope—

Figure 2 is a top view of the anchor as it rests upon any flat surface with the weighted members folded together without the attachment of the anchor rope—

Figure 3 is a section at the line 3—3 of Figure 2—

Figure 4 is a view similar to Figure 2 but with the weighted members dropped down so as to assume a position parallel with the base—

Figure 5 is a side elevation of the parts in the position shown at Figure 4, with rope attached in preferred manner, and Figure 6 is a view similar to Figure 2 but showing a slight modification of the base.

Similar numerals of reference denote like parts in the several figures of the drawings.

Part 1 is the base of the mushroom type having rising from its center a post 2 which terminates at its upper end in a stop 3 and is perforated as at 4 for the purpose presently to be explained.

Parts 5 are heavy members, preferably hemi-spherical, that are pivoted to the post 2 by means of a bolt 6 passed through ears 7 extending from the bottoms of these members and through the perforation 4, and these members preferably have flat inner faces and lugs 8 which abut against the stop 3 when assembled for use as shown at Figure 3. Also said members have ears 9 that extend upwardly therefrom and are perforated as shown at 10.

The post 2 and the members 5 constitute the shank of the anchor.

The base preferably has openings 11 there-

through to facilitate the lowering and raising of the anchor.

When the parts are in the position as shown at Figures 2 and 3, the perforations 10 will register, and it is possible to reeve an anchor rope through these perforations and knot it in an ordinary manner and then throw the anchor overboard when it will assume the position shown at Figure 1, the anchor rope being designated by the numeral 12.

When the anchor is pulled inboard, the rope may be detached and the members 5 dropped down to the position seen at Figure 4, and the lugs 8 will abut the post 2 and thereby prevent said members from contacting the base, thus doing away with rattling, and when the parts are in this position said members will be partly housed within the base and will be parallel therewith, thus presenting a flat structure which may readily be stowed away and not roll or rock.

The ball shaped assembled members 5 of the shank give the necessary weight so that when the anchor touches bottom it will be held on its side thus facilitating its grip.

If desired, the perimeter of the base may have prongs 13 as shown at Figure 6 to increase the grip of the anchor.

There are no pins to insert, prongs to bend in place, or stock to adjust, but it is merely necessary to put a cable or rope through the perforations 10 when the weight members are folded upwardly and knot such cable or rope, or to reeve such cable or rope through said perforations while said members are dropped down and tie with a bowline, and as soon as said cable or rope becomes taut in the water all necessary adjustments are made. Also there are no arms, flukes, shanks, or any surfaces that would foul the cable or rope.

The exterior surfaces of the members 5 may be of any shape or contour, and the invention is not limited in this respect.

So far as the attachment of a rope or cable through the ears 9 of the sections 5 is concerned, my invention is not limited in this respect, and such rope or cable may be secured in any manner when the members 5 are lying flat as shown at Figure 5, and the invention is not limited in this respect.

The attachment of the rope or cable to the members 9 by means of a bowline or by reeving such rope or cable through one ear 9 and tying a large knot 14 at the bottom so as to prevent slipping through the hole in such ear and then passing it downward to the other ear, as shown at Figure 5, is preferable to the tying of the rope to said ears as shown at Figure 1, since the anchor may always be stowed away without detaching the rope or cable.

What is claimed is:—

1. A mushroom anchor comprising a flat cup-like base having rising from its central portion a shank comprising a post, and a pair of hemi-spherical members pivoted to said post and perforated at their upper ends for reeving of an anchor rope.
2. A construction as in claim 1 further distinguished in that said post has a stop against which said members abut when swung to elevated position.
3. A construction as in claim 1 still further distinguished in that when the anchor is pulled inboard said members will drop downwardly and be housed within the base.
4. A mushroom anchor comprising a flat cup-shaped base having a shank consisting of an upright rising from its central portion and perforated at the top and having a stop, and a pair of heavy members having flat inner surfaces and suitably shaped outer surfaces, said members having holes at the top for the reeving of an anchor rope and abutting against said stop when closed and capable of dropping within said base and lying flat therein for convenient stowage.
5. A construction as in claim 4, with the addition that said members are provided with stops at their inner ends which stops abut against said upright, whereby the members when opened do not contact the base thereby preventing rattling.

In testimony whereof I affix my signature hereto.

ROBERT W. GIBB.
